[57] CLAIM

The ornamental design for a water closet, as shown and described.

DESCRIPTION

FIG. 1 is a front view of the first embodiment of a water closet embodying our new design;

FIG. 2 is a top view thereof;

FIG. 3 is a left side view thereof, the right side being a mirror image of the left side;

FIG. 4 is a perspective view thereof;

FIG. 5 is a front view of the second embodiment of a water closet embodying our new design;

FIG. 6 is a top view thereof;

FIG. 7 is a left side view thereof, the right side being a mirror image of the left side;

FIG. 8 is a perspective view thereof;

FIG. 9 is a front view of the third embodiment of a water closet embodying our design;

FIG. 10 is a top view thereof;

FIG. 11 is a left side view thereof, the right side being a mirror image of the left side; and,

FIG. 12 is a perspective view thereof.
